Charles H. Loop, Inventor
By Frank A. Ahlmann, Attorney

UNITED STATES PATENT OFFICE.

CHARLES H. LOOP, OF PAWHUSKA, OKLAHOMA, ASSIGNOR TO C. H. LOOP STEEL MANUFACTURING COMPANY, A CORPORATION OF OKLAHOMA.

TANK.

1,416,849.

Specification of Letters Patent. Patented May 23, 1922.

Application filed September 25, 1920. Serial No. 412,728.

To all whom it may concern:

Be it known that I, CHARLES H. LOOP, a citizen of the United States of America, and resident of Pawhuska, in the county of 5 Osage and State of Oklahoma, have invented certain new and useful Improvements in Tanks, of which the following is a specification.

This invention relates to tank construction, it being the primary object of the invention to provide novel means forming part of the tank for reenforcing the same in a manner to eliminate any possibility of 10 the tank bulging under the pressure of the 15 contents thereof.

A further object of the invention is to provide a tank having means to adjust the staves in the construction of the tank to move the staves in proper relation with each 20 other.

A still further object of the invention is the provision of novel means for connecting the staves at their adjacent edges to insure 25 against leakage at their points of connection.

With the foregoing and other objects in view, the invention consists in the details of construction, and in the arrangement and combination of parts to be hereinafter more 30 fully set forth and claimed.

In describing the invention in detail, reference will be had to the accompanying drawings forming part of this specification, wherein like characters denote corresponding 35 parts in the several views, and in which—

Figure 1 illustrates a vertical sectional view through a tank constructed in accordance with the present invention;

40 Figure 2 illustrates a fragmental sectional view of the supporting post and adjusting arm connection;

Figure 3 illustrates a sectional view on the line 3—3 of Figure 2;

45 Figure 4 illustrates a fragmental detail view of the connected edges of adjacent staves and the bracing rod;

50 Figure 5 illustrates a fragmental detail view of the connection between the staves and bottom of the tank;

Figure 6 illustrates the connection between the plates forming the bottom of the tank as employed in shop construction;

Figure 7 illustrates a fragmental detail

view of a modified form of connection between the plates of the bottom as employed in field construction;

Figure 8 illustrates a sectional view taken on the line 8—8 of Figure 6; and

Figure 9 illustrates a fragmental detail view partly in section showing the threaded supporting socket employed in the tank construction.

In these drawings, the tank includes a bottom section 5 and a head section 6, each of which sections is preferably circular in formation and formed of a plurality of plates disposed in parallel relation with each other, predetermined plates being provided with offset portions indicated at 7, the offset portions being of width to accommodate portions of the adjacent plate so that the side walls thereof will align with each other.

Disposed between the adjacent surfaces of adjacent plates is a suitable packing indicated at 8, the packing being of a length to extend the entire length of the plates, thus insuring a fluid tight connection between the plates, it being understood, however, that suitable bolt holes are provided in the plates and packing to receive the bolts 9.

The side walls of the tank include plates disposed in parallel relation with each other, which also have offset portions to accommodate the adjacent plate in a manner as described.

The plates have connection with the head 6 as clearly illustrated by Figure 5 of the drawing and in which the staves or plates which are indicated by the reference character 10, have their extremities formed at right angles as indicated at 11 to provide a securing flange, which flange is apertured to receive the securing bolts 12, which secure the staves and plates of the head together, there being provided suitable packing 13 disposed between the right angled portions of the staves and the plates of the head for insuring a fluid tight connection at their points of connection.

It might be further stated, however, that a reenforcing strip 14 extends around the tank, and overlies the portion 11 to secure the bolts 12 and insure a close fit between the angular portions 11 and plates of the head.

Supported between the bolts 12 are the strips 15, in the nature of packing strips which strips cause the reenforcing strip to bulge when the bolts 12 are secured in their

proper position, thereby providing means to cause the reenforcing strip to closely engage the bolts 12.

Supported within the tank is an upright 5 or supporting post 16, which post is formed in sections, the upper section 17 of which is threaded in the socket member 18, secured to the head 6, substantially centrally thereof, and held in such position by means of the 10 bolts 19, which pass through the head and through suitable openings in the socket member 18.

The lower extremity of the section 17 is threaded to accommodate the turn buckle 15 20, which turn buckle also cooperates with the threaded extension 21 of the post 16, the lower extremity of the post 16 being positioned in the threaded socket member 22 which is bolted to the bottom 5 of the tank 20 as by means of the bolts 23.

From the foregoing, it is obvious that by rotation of the turn buckle 20, the head and bottom of the tank may be moved with respect to each other to take up for any bulging 25 of either the head or the bottom, so that the head 6 and bottom 5 may be held in proper relation with each other at all times.

The adjusting rods 24 form an important 30 feature of the invention, the adjusting rods having their outer extremities formed at right angles to the body portions thereof, which outer extremities are bolted to the staves 10 as by means of the bolts 25, as clearly shown by Figure 4 of the drawing.

These adjusting rods are also formed in 35 sections, the inner section of each rod being bolted to the circular securing member 26 which is secured to the supporting post 16 at a point substantially intermediate the ends 40 thereof, as by means of the clips 27, which are positioned on opposite sides of the securing member 26, as illustrated more clearly by Figure 2 of the drawing. The outer extremity of each inner section is threaded as 45 at 28 to accommodate the turn buckle 29 which also operates over the threaded portion 30 of the outer section of the adjusting rod associated therewith, so that movement of the turn buckle will result in a relative 50 movement of the staves to compensate for any bulging thereof.

As shown, these adjusting rods are arranged in pairs having their inner sections converging towards the securing member 55 26 the ends being secured as by means of the bolts 31 which pass through the ends of the inner sections and through the circular securing member 26. The outer sections of these adjusting rods diverge as clearly 60 shown in Figure 1 of the drawings, so that the staves will be braced at points adjacent to the ends thereof.

A securing member 32 is supported by the

supporting post at a point adjacent to the upper extremity thereof and this securing 65 member 32 provides means for connecting the adjusting rods 33 to the supporting post 16, the rods 33 being also provided with turn buckles 34, whereby the sections of the rods may be adjusted with respect to each 70 other and since these rods 33 have connection with the head 6, it is obvious that movement of the turn buckles 34 will result in a movement of the head 6 to cause the same to maintain a proper position with respect 75 to the staves 10.

Secured to the inner surface of the offset portion of each of the staves at a point where the adjacent edges of staves contact with each other, is an angle iron indicated 80 at 35, which angle irons extend the entire length of the tank and are bolted thereto as by means of the bolts 9 the heads of which extend beyond the outer periphery of the tank proper, thereby permitting an operator 85 to tighten the bolts from a point exteriorly of the tank to tighten the connection between adjacent staves in the event that a leaking connection is detected.

In the form of connection as illustrated by 90 Figure 7 of the drawings, it will be seen that the offset portion has been eliminated, the adjacent edges of the staves overlapping as, indicated at 36, the overlapping edges being connected as by means of the bolts 37. 95 It has been found in practice that this form of connection is more desirable for shop use than the connection illustrated by Figure 6, the connection being more easily constructed, while the form of invention as 100 illustrated by Figure 6 is more adaptable for field use.

While I have shown and described a tank circular in cross section, it is to be understood that the contour of the tank may be 105 changed to meet various requirements such change being within the scope of the invention.

It might be further stated that the tank is provided with suitable manholes and inlet 110 or exhaust pipes, the locations of which may be determined by persons constructing the tank.

I claim:

A tank including a head and a bottom, 115 staves connecting the head and bottom, each of the staves having right angled ends, a reinforcing strip positioned over the right angled ends, bolts extending through the right angled ends, strips and bottom for securing the same together, and packing strips of material disposed between the bolts and under the reinforcing strips for causing the strips to bulge.

C. H. LOOP.
